DESIGN FOR AN INSECTICIDE HOLDER

Frank G. McWilliams, Lakewood, Ohio

Application March 26, 1934, Serial No. 51,197

Term of patent 14 years

To all whom it may concern:

Be it known that I, FRANK G. McWILLIAMS, a citizen of the United States, residing at Lakewood, in the county of Cuyahoga and State of Ohio, have invented a new, original, and ornamental Design for Insecticide Holder, of which the following is a specification, reference being had to the accompanying drawing, forming a part thereof, in which—

I claim:—

The ornamental design for an insecticide holder substantially as shown.

FRANK G. McWILLIAMS.
